UNITED STATES PATENT OFFICE.

FRED W. LUNDY, OF DENVER, COLORADO.

PRESSURE INDICATOR.

Application filed January 16, 1926. Serial No. 81,866.

This invention relates to devices for indicating the vapor pressure in automobiles.

Internal combustion engines are employed almost universally for furnishing the motive power for automobiles and all require some cooling means. With one notable exception, the internal combustion engines used in connection with automobiles are water cooled and employ an element known as a radiator. Under normal conditions the radiator keeps the cooling liquid below the evaporation point.

On warm days and when the engine is heavily loaded or when for some reason the water does not circulate properly, the radiator is insufficient to keep the water cool and consequently vapor will be thrown off inside the radiator and will escape thru an overflow pipe provided for this purpose. The location of this overflow pipe on the radiator of an automobile is such that the escaping vapor is not visible from the driver's position. Vapor escaping in any considerable amount is very undesirable as it not only depletes the meager water supply of the radiator but, in winter when alcohol or other nonfreezing solution is used, it wastes the nonfreezing agent making operation much more expensive than necessary.

Often the vapor rises so rapidly that the drain pipe becomes inadequate to carry it away and the whole cooling system is put under a considerable pressure. Probably many leaks which occur in the cooling system could be avoided if the driver but knew that the cooling system was under pressure. Many accidents have occurred in which persons have been more or less seriously burned when removing the radiator cap unaware of the pressure inside the radiator.

In order that the driver may be apprised of the pressure conditions within the radiator, thermometers have been constructed which project through the radiator caps and have the bulb within and the stem without the cap so that the driver may at all times tell the actual thermal condition of the cooling water. To arrive at pressure conditions from known thermal conditions would necessitate considerable calculation inasmuch as the pressure does not vary directly with the temperature.

Due to the resistance in the small drain pipes provided on radiators of this type, sufficient pressure will be had to raise the indicator of a pressure gauge, substantially at

the same time that evaporation losses become appreciable. The gauge will rise and fall indicating evaporation until the pressure becomes sufficient to maintain the indicator in the raised position indicating pressure. It is therefore evident that if a pressure indicating device is applied to the radiator, it will serve to indicate the presence of steam in any considerable amount.

It is the object of this invention to produce a pressure responsive device which is adapted to be attached to a radiator and which will indicate the pressure of steam in any considerable amount.

This invention, briefly described, comprises a tubular member having a cylindrical opening in which a light piston is mounted so as to reciprocate. This member is arranged in a vertical position and has its lower end in communication with the interior of a radiator. The piston will normally occupy the lowermost position and will extend downwardly into the radiator. When the pressure increases, the piston will be moved upwardly. The tubular member has an opening through which the piston may be seen and the piston has its outer surface colored red and green; normally the green color is visible but when abnormal conditions prevail the red colored portion is visible.

Having thus briefly described my invention, I will now proceed to describe the same in detail, and for this purpose reference will be had to the accompanying drawing where one embodiment of the invention has been illustrated and in which:

Fig. 1 is a side elevation of the device looking forwardly from the driver's seat;

Fig. 2 is a vertical section taken on line 2-2, Fig. 1 and shows the parts in normal or inoperative position;

Fig. 3 is a section like that shown in Fig. 2 but with the parts shown in operative position;

Fig. 4 is a vertical section through the plunger or piston; and

Fig. 5 is a side elevation of an engine and radiator, the latter being shown in section and with my improved pressure device in place thereon.

Numeral 1 indicates a cap adapted to fit the fill opening of a radiator. This cap may be constructed in any suitable manner but has been shown as having an externally threaded portion 2, a flange 3 and a recess

4. The cap has a central opening 5 in which a tubular cylindrical member 6 is located; this tubular member terminates a short distance below the top of the cap but extends upwardly a considerable distance in the manner shown. The lower end of the tube 6 has an inwardly extending flange 7 and the upper end is provided with a cap 8 which may be constructed as shown or made more or less ornamental. Near the upper end of member 6 directly below the cap 8, two diametrically opposed openings 9 are provided so that light can pass entirely through the tube at this point. A short distance below the opening 9 another opening is provided and this has been designated by numeral 10. Within the tubular member 6 is a plunger or piston 11 which may be made of any suitable material such as cork, glass, celluloid or metal. The plunger illustrated has been formed from aluminum and has its lower end closed in the manner indicated by numeral 12 in Fig. 4. The outside diameter of the plunger is slightly less than the inner diameter of the tube 6 and it is provided with a short ring 13 whose outside diameter is substantially the same as the inner diameter of the tube 6. The ring 13 may be integral, as shown, or made of a separate piece suitably secured thereto. A cap 14 may be secured to the upper end of the plunger for the purpose of preventing water from accumulating in the plunger. The plunger is inserted into the tube 6 from the top and will normally assume a place in which the ring 13 rests upon the flange 7. A washer 15 is secured to the bottom 12 by a screw 16. The function of this washer is to act as a stop for limiting the upward movement of the plunger and to act as a seal which will prevent the escape of steam as it is evident that the ring 13 cannot fit the inside of the tube 6 closely enough to make a steam tight fit. That part of the outer surface of the plunger that lies between the ring 13 and cap 14 is colored; the upper half G being colored green and the lower half R red. When the parts are in normal or inoperative position (Figs. 1 and 2) the green color is visible through the opening 10 but when the plunger has been raised to the uppermost position shown in Fig. 3 the red color is visible through the opening 10. At night it would be difficult to distinguish

what color is visible through the opening 10 55 and for the purpose of enabling the driver to read the signal at night the holes 9 have been provided. When the plunger is in the position shown in Figs. 1 and 2, light from the roadway will pass through these holes 60 but when the plunger is in the position shown in Fig. 3, the passageway through the openings 9 will be obstructed which fact can readily be detected by the driver at night because no light is visible through these 65 openings.

In Fig. 5 I have illustrated the several elements of the combination in which my invention is to be used, numeral 17 indicating the engine, 18 the water jacket and 19 the 70 radiator to which the pressure indicator is attached.

I am aware that temperature responsive means have been employed in a similar combination but as far as I am aware, no one 75 has ever employed the vapor pressure to produce indications that vary with the temperature and I therefore intend to claim this combination broadly as well as my apparatus specifically.

Having now described my invention what I claim as new is:

The combination with a cap for the filler spout of an automobile radiator of a hollow tubular member provided with an axial cylindrical opening mounted on said cap, the lower end of said opening being in communication with the interior of the radiator, a piston slidably mounted in said opening, said piston having one end in communication 90 with the interior of the radiator and the other in communication with the atmosphere, means for limiting the downward movement of said piston, said means permitting the piston to move upwardly when 95 sufficient pressure is applied to the lower end thereof and a combined stop and sealing means for limiting the upward movement of the piston and for preventing the escape of vapor, said tubular member having 100 a diametrically opposed openings at a point above the normal position of the upper end of the piston whereby said openings will be obstructed only when the piston is in raised position.

In testimony whereof I affix my signature.

FRED W. LUNDY.
